HOSE CONNECTOR FOR VACUUM CLEANERS

Robert C. Lampe, Stamford, Conn., assignor to
 Electrolux Corporation, Old Greenwich, Conn.,
 a corporation of Delaware

Application December 31, 1952, Serial No. 328,949

9 Claims. (Cl. 183—37)

1

This application is a continuation-in-part of copending application Serial No. 140,394, filed jointly by Gustaf Einar Lofgren, John T. Ferraris and myself on January 25, 1950, now Patent No. 2,641,330 dated June 9, 1953, and relates back thereto for all common subject matter.

The present invention relates to vacuum cleaners and more particularly to vacuum cleaners of the enclosed bag type.

In cleaners of this type it has been common practice to provide a removable closure for the dust bag compartment and to connect the suction hose to an inlet conduit rigidly carried by and extending through the closure. With such an arrangement, if it were desired to pivotally connect the closure to the casing of the vacuum cleaner, and this is essential in the case of a cleaner having means for automatically opening the closure when the bag should be replaced, the connection of the hose to the closure would seriously interfere with the pivotal movement of the former.

Accordingly, it is one of the objects of my invention to provide an arrangement whereby a closure may be pivotally connected to the casing and pivoted between closed and open positions without any substantial interference or resistance from the hose.

In accordance with my invention, the hose is not connected directly to the closure itself, but to a separate hose connector member which carries the inlet conduit and which is pivoted on the closure. I also provide parallel motion linkage, of which the closure constitutes one link, for maintaining the hose connector member and the inlet conduit carried thereby parallel to themselves. The closure is preferably pivoted to the casing about a substantially horizontal axis disposed beneath the opening to the dust bag compartment, and hence pivots downwardly when opened, carrying the hose connector with it. In order that the latter, which moves parallel to itself, shall not extend when the closure is opened above the bottom of the opening to the bag compartment, the bottom of this opening must be disposed above the floor or other surface supporting the cleaner a distance at least as great as the vertical extent of the hose connector, and it is an additional feature of my invention that the hose connector may have a

2

vertical extent which is substantially less than that of the opening, thereby making it possible to have the opening much closer to the floor than would be the case if the entire closure member were mounted for parallel motion.

Other objects and advantages of my invention will be apparent from the following description in conjunction with the accompanying drawings which form part of this specification, and in

10 which:

Fig. 1 is a perspective view showing a vacuum cleaner embodying my invention;

Fig. 2 is a view similar to Fig. 1 showing a portion of the vacuum cleaner and with certain 15 parts in a different position;

Fig. 3 is a front view of the vacuum cleaner shown in Fig. 1;

Fig. 4 is a cross-sectional view taken on the line 4—4 of Fig. 3; and

20 Fig. 5 is a cross-sectional view taken on the line 5—5 of Fig. 3.

Referring to the drawings reference character 10 designates a hollow casing provided with a pair of runners 12 for supporting it in a horizontal position on a horizontal surface. The left-hand end of casing 10, as viewed in the figures, encloses a dust receptacle compartment 14 having an opening 16 disposed in a vertical plane. A dust receptacle 18 is adapted to be inserted into compartment 14 through the opening 16. The receptacle includes a bag portion 20 made of air pervious material, such as porous paper, one end of which is secured to a relatively rigid disc member 22, preferably made of cardboard. A preferably circular opening 24 is formed in the disc member and in the adjacent end of the bag portion. This opening may be covered by a sheet of elastic material 26 having an opening 28 therethrough of normally reduced size, but which may be enlarged by stretching of the elastic material, as hereinafter described, so as to approximate the size of the opening 24. The size and configuration of the disc 22 is such that it may seat in airtight relationship against a gasket 30 secured in the opening 16.

In Fig. 2 there is shown a perforated plate 32 located within the compartment 14 adjacent to the opening 16. This plate is movable for the purpose of ejecting the dust receptacle 18 from the compartment 14 and in Fig. 2 is shown a

position to which it has moved for the purpose of ejecting the receptacle. This plate 32 may be moved rearwardly into the compartment and retained therein in order that the dust receptacle may be inserted. However, the ejection mechanism of which the plate 32 forms a component, is no part of the present invention and consequently is not further illustrated herein. For a complete description of this mechanism reference may be had to the specification of parent application Serial No. 140,394, now Patent No. 2,641,330.

Below the opening 16 the casing of the cleaner is formed with a wall 34 forwardly from which projects a pair of members 36. Pivotaly mounted on these members about a horizontal axis 38 is a structure designated generally by reference character 40. This structure serves as a partial closure for the opening 16 and may be pivoted from the closed position shown in Figs. 1, 3, 4 and 5 to the open position shown in Fig. 2. This structure includes a lower portion 42 which extends substantially the entire width of the casing, as is seen from Figs. 1 and 3, and two spaced side portions 44 and 46 which extend upwardly therefrom. A coil spring 48 disposed about the axis 38 tends to pivot the structure 40 to open position, while a latch member 50 retains the structure in closed position, as shown in Fig. 5. The latch member is pivoted to the inner side of wall 34 at 52 and may be released manually by means of a button 54 secured to the upper end of a rod 56 which is carried by one of the side portions 46.

A member 58 is pivotally mounted in the space between the side portions 44 and 46 about a pivot 60. The lower portion of member 58 is comprised of resilient material 61. The member 58 carries a hose connector 62 to which may be attached a flexible suction hose 64 and which communicates with an inlet conduit 66 which extends inwardly from the member 58. A gasket 67 surrounding conduit 66 is carried by member 58.

A link 68 is pivotally connected at 70 to one of the members 36, and is pivotally connected at 72 to the member 58. The distance between the pivot points 38 and 60 on the one hand and the pivot points 70 and 72 on the other hand are equal and consequently the closure member 40 and the link 68 together constitute parallel motion mechanism which assures that the member 58 and the inlet conduit 66 carried thereby and the hose 64 connected thereto will remain parallel to themselves as the structure 40 moves between open and closed positions. The lower portion 42 of the structure 40 is hollow so that it may receive the inlet conduit 66 when the structure 40 is moved to the open position, as shown in Fig. 2.

It will be noted that the vertical extent of the opening 16 is greater than the vertical distance from the bottom of the opening 16 to supporting surface on which the runners 12 rest. Although the vertical extent of the structure 40 is somewhat greater than that of the opening 16, the vertical extent of the member 58 is less than that of the opening, and consequently when the structure 40 is pivoted to the open position as shown in Fig. 2, in which position the bottom of the member 58 rests on the supporting surface, the entire assembly consisting of the structure 40 and the member 58 is below the lower edge of the opening 16. If the entire structure 40 were mounted for parallel motion, the bottom of the opening 16 would have to be

disposed above the floor a distance at least as great as the vertical extent of the structure 40 in order that the top of this structure, when in open position, would be below the bottom of the opening.

The above described device operates as follows:

Starting with the structure 40 in open position, the plate 32 may be pushed back into the compartment 14 and the dust receptacle 18 inserted into the compartment and the disc member 22 seated against the gasket 30. Thereafter, the structure 40 is pivoted to closed position, and during this pivotal movement the member 58 travels in an arcuate path, but the inlet conduit 66 remains parallel to itself. When the end of this conduit strikes the elastic sheet material 26 it stretches the opening 28 until the conduit enters the opening, the elastic material 26 then surrounding the conduit as shown in Fig. 4. The gasket 67 carried by the member 58 around the inlet conduit 66 presses against the central portion of the disc 22 so as to securely retain the latter in position against the gasket 30. Engagement of the latch 50 retains the structure 40 in this closed position. Consequently, dirt-laden air entering through the hose 64 may pass through the inlet conduit 66 into the interior of the dust receptacle 18, where the dust is retained while the air may pass through the porous bag portion 20.

When it is desired to remove the dust receptacle, depression of the button 54 releases the latch 50, thus enabling the spring 48 to pivot the structure 40 to the open position shown in Fig. 2, the member 58 again moving parallel to itself until the resilient lower part 61 thereof strikes the floor or other supporting surface, thus arresting further movement of the structure 40. Inasmuch as the member 58 remains parallel to itself in all positions, the structure 40 may be opened without bending the hose 64 but by merely sliding the latter forward a short distance. It has been determined that such movement of the hose offers but little resistance to the opening to the structure 40, thus permitting the use of a relatively light spring 48 while at the same time assuring complete opening of the structure.

As previously stated, when the structure 40 is in open position both it and the member 58 are disposed below the lower edge of the opening 16 and consequently do not interfere with the removal of the dust receptacle 18.

While I have shown one more or less specific embodiment of my invention, this has been done for illustration only and is not to be considered as limiting the scope of my invention, which is to be determined from the appended claims.

60 I claim:

1. In a vacuum cleaner, a casing defining a dust receptacle compartment having an opening, a dust receptacle insertable into and removable from said compartment through said opening, a structure pivotally connected to said casing and pivotal to a position in front of said opening, a member pivotally mounted on said structure, hose coupling means carried by said member, and a link pivotally connected to said casing and said member, said structure and said link comprising parallel motion mechanism for maintaining said member parallel to itself as it is moved towards and away from said opening by the pivotal movement of said structure.

75 2. In a vacuum cleaner, a casing defining a

dust receptacle compartment having an opening disposed in a substantially vertical plane, a dust receptacle insertable into and removable from said compartment through said opening, structure pivotally connected to said casing about a substantially horizontal axis disposed beneath said opening, said structure being pivotal to a position in front of said opening, a member pivotally mounted on said structure, hose coupling means carried by said member, and a link pivotally connected to said casing and to said member, said structure and said link comprising parallel motion mechanism for maintaining said member parallel to itself as it is moved towards and away from said opening by the pivotal movement of said structure.

3. In a vacuum cleaner, a casing defining a dust receptacle compartment having an opening disposed in a substantially vertical plane, means for supporting said casing on a surface with the bottom of said opening spaced above said surface, a dust receptacle insertable into and removable from said compartment through said opening, structure pivotally connected to said casing about a substantially horizontal axis disposed beneath said opening, said structure being pivotal to a position in front of said opening, a member pivotally mounted on said structure, hose coupling means carried by said member, and a link pivotally connected to said casing and to said member, said structure and said link comprising parallel motion mechanism for maintaining said member parallel to itself as it is moved towards and away from said opening by the pivotal movement of said structure, said member extending below said structure when the latter is pivoted downwardly towards said surface so that said member contacts said surface and limits pivotal movement of the structure.

4. In a vacuum cleaner, a casing defining a dust receptacle compartment having an opening disposed in a substantially vertical plane, means for supporting said casing on a surface with the bottom of said opening spaced above said surface, a dust receptacle insertable into and removable from said compartment through said opening, structure pivotally connected to said casing about a substantially horizontal axis disposed beneath said opening, said structure being pivotal to a position in front of said opening, a member pivotally mounted on said structure, said member having a lower portion comprised of relatively soft resilient material, hose coupling means carried by said member, and a link pivotally connected to said casing and to said member, said structure and said link comprising parallel motion mechanism for maintaining said member parallel to itself as it is moved towards and away from said opening by pivotal movement of said structure, said lower portion of said member extending below said structure when the latter is pivoted downwardly towards said surface so that said resilient material contacts said surface and limits downward pivotal movement of the structure.

5. In a vacuum cleaner, a casing defining a dust receptacle compartment having an opening, a dust receptacle insertable into and removable from said compartment through said opening, said receptacle including a relatively stiff end portion formed with an inlet aperture, structure pivotally connected to said casing and pivotal to a position in front of said opening, a member pivotally mounted on said structure, hose coupling means carried by said member, an inlet conduit carried by said member and extending

inwardly therefrom for insertion into said inlet aperture when said structure is pivoted to said position, and a link pivotally connected to said casing and said member, said structure and said link comprising parallel motion mechanism for maintaining said member and said inlet conduit parallel to themselves as they are moved towards and away from said opening by the pivotal movement of said structure.

6. In a vacuum cleaner, a casing defining a dust receptacle compartment having an opening disposed in a substantially vertical plane, a dust receptacle insertable into and removable from said compartment through said opening, structure pivotally connected to said casing about a substantially horizontal axis disposed beneath said opening, said structure having an extent normal to said axis at least as great as the vertical extent of said opening and being pivotal to a position in front of said opening, a member pivotally mounted on said structure, hose coupling means carried by said member, and a link pivotally connected to said casing and said member, said structure and said link comprising parallel motion mechanism for maintaining said member parallel to itself as it is moved towards and away from said opening by the pivotal movement of said structure, the vertical extent of said member being substantially less than said vertical extent of said opening.

7. In a vacuum cleaner, a casing defining a dust receptacle compartment having an opening disposed in a substantially vertical plane, means for supporting said casing on a surface with the bottom of said opening spaced above said surface a distance less than the vertical extent of said opening, a dust receptacle insertable into and removable from said compartment through said opening, structure pivotally connected to said casing about a substantially horizontal axis disposed beneath said opening, said structure having an extent normal to said axis at least as great as said vertical extent of said opening and being pivotal to a position in front of said opening, a member pivotally mounted on said structure, hose coupling means carried by said member, and a link pivotally connected to said casing and said member, said structure and said link comprising parallel motion mechanism for maintaining said member parallel to itself as it is moved towards and away from said opening by the pivotal movement of said structure, the vertical extent of said member being no greater than the distance between the bottom of said opening and said surface.

8. In a vacuum cleaner, a casing defining a dust receptacle compartment having an opening disposed in a substantially vertical plane, a dust receptacle insertable into and removable from said compartment through said opening, structure pivotally connected to said casing about a substantially horizontal axis disposed beneath said opening, said structure comprising a lower portion having a lateral extent substantially equal to the width of said opening and two spaced side portions extending upwardly from said lower portion, a member pivotally mounted between said side portions, hose coupling means carried by said member, and a link pivotally connected to said casing and to said member, said structure and said link comprising parallel motion mechanism for maintaining said member parallel to itself as it is moved towards and away from said opening by the pivotal movement of said structure.

7
9. In a vacuum cleaner, a casing defining a dust receptacle compartment having an opening disposed in a substantially vertical plane, a dust receptacle insertable into and removable from said compartment through said opening, structure pivotally connected to said casing about a substantially horizontal axis disposed beneath said opening, said structure comprising a lower hollow portion having a lateral extent substantially equal to the width of said opening and two spaced side portions extending upwardly from said lower portion, a member pivotally mounted between said side portions, hose coupling means carried by said member, an inlet conduit carried by said member and extending inwardly therefrom, and

5
10
a link pivotally connected to said casing and said member, said structure and said link comprising parallel motion mechanism for maintaining said member and said inlet conduit parallel to themselves as they are moved towards and away from said opening by the pivotal movement of said structure, said inlet conduit being received within said lower hollow portion when said structure is pivoted away from said opening.
